COMBINATION COLLAPSIBLE BOAT AND CARRYING CASE

John E. Thomson, Pittsburgh, Pa., assignor of one-third to Wilfred S. Stone, Wayne, Ill., and Anthony S. Zummer, Evanston, Ill.

Filed June 5, 1961, Ser. No. 114,793
3 Claims. (Cl. 9—2)

This invention relates to an improved construction for a collapsible boat and more particularly to a collapsible boat which also provides a self-contained carrying case for carrying boat accessories and other articles, such as, fishing tackle, clothing and other desired articles.

Although the mobility of people has increased substantially over the period of years, many sportsmen, especially fishermen, find that their mobility is handicapped inasmuch as it is quite cumbersome to carry a boat with them on all trips. Furthermore, it has been found in certain instances that given bodies of water may be inaccessible by automobile so that it is impractical to bring a boat to a given body of water although the fishing may be particularly good in that body of water. Many types of lightweight collapsible boats are provided; however, most of these boats have a fabric construction so that they are dangerous to use on a foreign body of water, inasmuch as the fabric may be easily punctured by a submerged stump, limb or other object. Other collapsible boats make no provision for providing a unitary package which contains not only the boat and fishing tackle but also provides room for carrying fishing clothes and other desirable articles on a fishing trip. Therefore, it is one of the principal objects of the herein disclosed invention to provide a combination collapsible boat and carrying case which provides a device for carrying extra clothes and other equipment with the collapsed boat to provide a package which may be readily transported by a single individual.

It is another object of the herein disclosed invention to provide a collapsible boat hull which has a fixed lower hull which provides necessary buoyance for an individual occupant and the freeboard of the hull is foldable over the hull to close the open side of the hull, thereby providing a convenient carrying case.

It is a further object of the herein disclosed invention to provide a collapsible boat wherein all of the parts of the boat are contained within the collapsed boat hull.

It is still another object of the herein disclosed invention to provide an improved seat construction for use in a collapsible boat hull.

It is a still further object of the present invention to provide a safe construction for a collapsible boat hull in which the water line of the boat is below any folding seam.

Other objects and uses of the herein disclosed invention will become readily apparent to those skilled in the art upon a perusal of the appended specification in light of the accompanying drawings in which:

FIGURE 1 is a side view of a collapsible boat embodying the herein disclosed invention;

FIGURE 2 is a plan view of the boat shown in FIGURE 1;

FIGURE 3 is a perspective view of the boat shown in FIGURE 1, showing the boat in use;

FIGURE 4 is a fragmentary perspective view showing how a seat is mounted in the boat shown in FIGURE 1;

FIGURE 5 is a perspective view showing the boat in FIGURE 1 in a collapsed attitude so that it is a carrying case;

FIGURE 6 is a cross-sectional view of a portion of a freeboard which constitutes a portion of the boat shown in FIGURE 1 showing the operation of a latch to hold

2

the boat in its closed attitude, and also shows the construction of an integral handle for the instant device;

FIGURE 7 is a cross-sectional view showing how the seat back is attached to the boat hull; and

FIGURE 8 is a perspective view showing the hull in a partially folded attitude.

Referring now to the drawings, a combination collapsible boat and carrying case, generally indicated by numeral 10, consists of a boat hull 12 which includes a lower rigid hull 14 having a handle 16 therein and a foldable freeboard sealingly and hingedly attached to the lower hull, a latch 20 for holding the freeboard in a closed position, a pair of carlocks 22 mounted on the boat hull, and a seat 24 removably mounted within the boat hull to provide a convenient resting place for an occupant of the boat.

The lower hull 14 has a lightweight construction in that it is made up of a plurality of sheets of aluminum sealingly fixed to each other. A bottom 26, which is rectangular, is made of a piece of sheet aluminum and has a side 28 sealingly fixed to one edge of the bottom. The side 28 has the handle 16 formed therein as will be described hereinafter. The side 28 is trapezoidal in this instance and has its shorter parallel edge fixed to one edge of bottom 26. The hull 14 includes a rectangular stern 30 with one edge sealingly fixed to a second edge of the bottom and a second edge sealingly fixed to one of the non-parallel edges of side 28. A second side 32 is also trapezoidal in form and has its shorter parallel edge sealingly fixed to a third edge of the bottom and a non-parallel edge sealingly fixed to one edge of the stern. The hull 14 is completed by rectangular bow 34 which has one edge sealingly fixed to a fourth edge of the bottom and a pair of opposite edges sealingly fixed to non-parallel edges of sides 28 and 32. It may be noted that the volume of the lower hull is sufficiently great so that there is sufficient buoyant force to support a man in the boat plus the weight of the boat.

The foldable freeboard 18 which is hingedly and sealingly mounted on the lower hull serves a multiple purpose in that it acts as a combination splashboard and support for the lower hull when the instant device is used as a boat and as a cover for the lower hull when the device is used as a carrying case. The freeboard includes a trapezoidal side panel 36 which has its longer parallel edge hingedly and sealingly connected to the longer parallel edge of side 28. The edges of the side 28 and the side panel 36 are connected by a sealing hinge 38. In this instance, the sealing hinge 38 is an extruded medium density polyethylene material which overlaps both edges to hold the edges adjacent to each other. It is evident how the hinge 38 provides a combination seal and hinge between the two edges. Thus, the side panel may be folded into the lower hull as will be described hereinafter. A triangular side panel 40 is hingedly and sealingly connected to the side panel 36 by a sealing hinge 42. The triangular side panel 40 has one of its angles, that is, the angle adjacent to the lower hull, equal to the acute angle of the trapezoidal side panel 36 which angle is formed by the longer parallel edge of side panel 28 and the edge adjacent to triangular side panel 40. Hingedly and sealingly connected to triangular side panel 40 is a stern panel 46 which has one edge hingedly and sealingly connected to one edge of the triangular side panel 40 by means of a sealing hinge 48 and a second edge hingedly and sealingly connected to the upper edge of stern 30 by means of a sealing hinge 50. The stern panel 46 has a latch aperture 52 adjacent to its uppermost edge for cooperation with the catch 20 as will be described hereinafter.

The freeboard also includes a second triangular side panel 54 which is identical in configuration to triangular

side panel 40. The triangular side panel 54 has one edge hingedly and sealingly connected to one edge of stern panel 46 by means of sealing hinge 56. A second trapezoidal side panel 58 which is identical in its configuration to side panel 36 has one edge hingedly and sealingly connected to the longer parallel edge of side 32 by means of sealing hinge 60. One of the non-parallel sides of panel 58 is hingedly and sealingly connected to triangular side panel 54 by means of sealing hinge 62. Inasmuch as side panel 58 is identical to side panel 36 and triangular side panel 54 is identical to triangular side panel 40, it is clear that the side panels 54 and 58 have adjacent equal angles which equal angles have their apexes at a common point. A third triangular side panel 64 has one edge hingedly and sealingly connected to a non-parallel edge of said panel 58 by means of a sealing hinge 66. In this instance, the triangular side panel 64 is identical in configuration to the triangular side panel 54 and one angle of the triangular side panel 64 is equal to an acute angle of the side panel 58 and the apexes of the two equal angles are at a common point. Hingedly and sealingly connected to the triangular side panel 64 is a bow panel 68 which has one edge connected to one edge of the triangular side panel 64 by means of a sealing hinge 70. A second edge of the bow panel is connected to one edge of the bow 34 by means of a sealing hinge 72. The bow panel 68 has a catch aperture 74 near its uppermost edge similar to catch aperture 52 of the stern panel. The last panel in the freeboard is a fourth triangular side panel 76 which is identical in configuration to the triangular side panel 64. The bow panel 68 has one edge connected to one edge of the triangular side panel 76 by means of a sealing hinge 78 and a second edge of the side panel 76 is hingedly and sealingly connected to a non-parallel edge of the trapezoidal side panel 36 by means of sealing hinge 80. It should be noted that the acute angle of the trapezoidal side panel 36 adjacent to triangular side panel 76 and the angle of triangular side panel 76 having substantially the same apex as the acute angle adjacent to the triangular side panel 76 are equal to each other.

As was mentioned above, the sealing hinge 38 is extruded of polyethylene material which allows the hinge to function both as a hinge and as a seal between the two edges. All of the aforementioned hinges 38, 42, 43, 60, 62, 66, 70, 72, 73 and 80, are of the identical material and of similar construction to provide suitable sealing hinges between their respective edges. It may be noted that at each of the corners 82, 84, 86 and 88, where a plurality of hinges meet, there is a point where there is no hinge material. Thus, a corner seal 90 of the same material as the hinges is sealingly fixed at each of these corners which corner seal is identical for all of the corners.

The seat 24 is mounted in a seat bracket 92 which is secured to bottom 26 and is held in a pair of seat catches 94 and 96 mounted on side panels 36 and 58, respectively. The seat includes a U-shaped frame 98 which has a frame bottom 100 mounted in seat bracket 92 and a pair of integral substantially vertical arms 102. A seat bottom 104 is pivotally mounted between the arms 102 adjacent to frame bottom 100 and a pair of combination seat-back fasteners and seat locks 106 are pivotally mounted adjacent the ends of the arms 102. The seat bottom includes a hoop 108 which is mounted on pivot 110 and has a fabric covering 112 on the hoop to provide a convenient resting place. A brace 114 is hingedly connected to the hoop 108 and to the frame bottom 100 to hold the seat bottom when the seat is in position.

The combination seat-back fastener and seat catch is identical in each instance. Each seat-back fastener and seat catch includes a back rod 116 which has fixed thereto a spacer 118 perpendicular to the back rod. Formed integral with and perpendicular to the spacer 118 is a frame rod 120 which extends through its respective frame arm 102 and is pivotal therein. A finger 122 formed integral with the rod 120 and perpendicular thereto is posi-

tionable within one of the seat catches mounted on its respective side panel. In order to complete the seat 24, there is a flexible fabric back 124 fixed to the back rods 116 of each of the combination back fastener and seat catches 106. The fabric back 124 provides a back support for the seat.

When the combination boat and carrying case is in a closed attitude, that is, when the freeboard is folded down into the lower hull, the catch 29 locks the freeboard into a closed attitude to hold the carrying case closed. As was mentioned above, the catch 20 is mounted on the trapezoidal side panel 36. The catch includes a base 126 which is sealingly fixed to side panel 36. The base has formed integral therewith a stud 128 which is extendable through apertures 52 and 74 of stern and bow panels 46 and 68, respectively. The stud has a pivotal arm 130 mounted thereon which arm may be aligned with the stud 128 to allow the stud and arm to pass through the apertures 52 and 74 and then may be pivoted 90 degrees to provide a convenient latch for keeping the freeboard in a closed attitude.

In order to provide a convenient carrying means for the case when the freeboard is in a closed attitude, the handle 16 is provided in the lower hull. The handle 16 includes an aperture 132 in side 28. The aperture 132 is formed by cutting a portion of the side 28 and rolling it to provide a convenient grip 134 which is formed integral with the side 28. In order to close the aperture 132, a handle cover 136 is sealingly fixed to bottom 26 and to side 28, thereby providing a handle recess in the lower hull and providing a convenient carrying means for the instant device.

From the foregoing description, it is readily apparent that a pair of oars such as oars 138 may be placed inside the lower hull along with the seat, fishing tackle, (not shown) clothing (not shown) and any other necessary items and the freeboard is folded over the top of the lower hull, thereby providing a collapsed boat and a convenient carrying case for necessary equipment. When the user arrives at a suitable location for using the instant device, it is necessary only for the user of the device to open the latch 20 by pivoting arm 130 about stud 128, thereby allowing the bow and stern panels to be moved upward and away from the side panel. The movement of the bow and stern panels also raises the two trapezoidal side panels and the four triangular side panels to form the hull. With the freeboard in its formed position, the seat is then placed into position. The bottom frame 100 is placed in the bracket and the brace 114 is positioned to hold the bottom. The trapezoidal side panels are moved relative to the combination seat back and seat fastener so that the fingers 122 are adjacent their respective seat catches. As was mentioned above, each of these catches is spaced slightly from its respective side panel and each seat catch has a slot therein into which is positioned the respective finger 122. The finger is then rotated to place the back bar 116 into a position substantially parallel to the arm of the seat frame. Thus, the seat frame holds the freeboard in its position. Also it should be noted that as force is applied to the back 124, the force serves to lock the seat into position, thereby holding the boat in its desired form. The oars are then placed in the oarlocks and the boat is ready for use.

It is readily apparent that inasmuch as the hull and freeboard is made of a rigid material such as aluminum sheet, the boat has an inherent degree of safety because it is not subject to puncture.

When the user is finished using the boat, it is necessary only for him to rotate the combination seat-back holder and seat lock and remove the fingers 122 from the seat catches. The seat may be removed from the bottom of the boat and the freeboard is then ready for folding.

After the necessary items are placed inside the lower

hull, the freeboard may be folded into the lower hull to close the top of the lower hull and provide a carrying case for the items contained within the lower hull. First the trapezoidal side panel 58 is moved toward the center and of course the side panel 36 follows after the side panel 58. It should be noted that the angles of each of the acute angles in the trapezoidal side panel are equal to the adjacent angles in the adjacent triangles. This construction allows the freeboard to fold flatly and uniformly, and it also allows the side panels to be rigid pieces of sheet metal. As the side panel 58 goes under the side panel 36, the stern and bow panels go over the side panel 36 so that the stud 28 passes through the apertures 52 and 74. The arm 130 is then pivoted as mentioned above to lock the panels into position and the carrying case is ready for transportation and the handle 16 is conveniently exposed for handy carrying of the instant device.

Although the instant device has been described in terms of using aluminum sheet metal and polyethylene sealing hinges, it is readily apparent that other materials and other similar constructions may be used in the use of the invention. It is also readily apparent that those skilled in the art may make various and sundry modifications and variations in the construction of a collapsible boat and carrying case embodying the herein disclosed invention. It is to be expressly understood that the present invention is in no way limited by the aforesaid disclosure but only by the appended claims.

I claim:

1. A combination carrying case and collapsible boat comprising, in combination, a rigid quadrangular bottom; a rigid first quadrangular side having one edge sealingly fixed to one edge of said bottom; a rigid quadrangular bow having one edge sealingly fixed to one edge of said bottom and a second edge sealingly fixed to one edge of said side; a rigid second side having one edge sealingly fixed to a second edge of said bottom and a second edge sealingly fixed to one edge of said bow; a rigid quadrangular stern having one edge fixed to a third edge of said bottom, a second edge sealingly fixed to the second-mentioned side and a third edge sealingly fixed to the first-mentioned side; a handle formed integral with the first-mentioned side; a rigid trapezoidal first side panel having its longest parallel side hingedly and sealingly connected to one edge of the first-mentioned side; a rigid first triangular side panel having one angle equal to the angle between the longer parallel edge and one of the non-parallel edges of the first side panel, said rigid first triangular side panel having its angle equal to one angle of the first side panel adjacent to said angle and having one edge hingedly and sealingly connected to one of the non-parallel edges of the first side panel; a rigid quadrangular bow panel having one edge hingedly and sealingly connected to one edge of the first triangular side panel and a second edge hingedly and sealingly connected to one edge of the bow; a rigid trapezoidal second side panel having its longer parallel edge hingedly and sealingly connected to one edge of the second side; a rigid triangular side panel having an angle equal to the angle between the longer parallel edge and the diagonal edge adjacent to the bow, said second triangular side panel having the apex of its angle equal to the angle in the second trapezoidal side panel adjacent to the apex of said angle of the trapezoidal side panel and having one edge hingedly and sealingly connected to said diagonal edge of the trapezoidal side panel and a second edge hingedly and sealingly connected to one edge of the bow panel; a rigid third triangular side panel having an angle equal to the angle between the other diagonal edge and the longer parallel edge of the trapezoidal second side panel, said third triangular side panel having one edge hingedly and sealingly connected to the other diagonal edge of the trapezoidal second side panel and the apex

of the equal angles in the third triangular side panel and the second trapezoidal side panel juxtaposed; a rigid quadrangular stern panel having one edge hingedly and sealingly connected to one edge of the third triangular side panel and a second edge hingedly and sealingly connected to one edge of the stern; a rigid fourth triangular side panel having an angle equal to an acute angle of the first trapezoidal side panel adjacent to the stern, said fourth triangular side panel having one edge hingedly and sealingly connected to a non-parallel edge of the first-mentioned trapezoidal side panel with apexes of the equal angles of the fourth triangular side panel and the first-mentioned trapezoidal side panel juxtaposed and a second edge hingedly and sealingly connected to one edge of the stern panel; a latch mounted on the first-mentioned trapezoidal side panel and engageable with the bow and stern panels to hold the bow and stern panels relative to the first trapezoidal side panel; a seat bracket mounted on the bottom; a U-shaped seat frame having the bottom of the U positioned in the seat bracket; a seat bottom pivotally mounted between the upright arms of the seat frame; a brace connected to the seat bottom and the bottom of the U of the seat frame to hold the seat bottom relative to the frame; a combination seat-back fastener and seat lock mounted on the upper portion of each of the arms of the U-shaped seat frame; each of said combination seat-back fasteners and seat locks including, a seat-back bar, a longitudinal spacer perpendicular to the seat back and arms, a frame rod perpendicular to the spacer and pivotally mounted in the upper portion of its respective seat-frame arm, and a finger perpendicular to the rod and parallel to the seat-back rods; a flexible seat back connected to the rod of each of said seat locks, and a seat catch mounted on each of the trapezoidal panels for locking the seat locks to the side panels by means of the catch finger.

2. A boat seat for use in a boat hull comprising, in combination; a U-shaped seat frame having the bottom of the U positionable on the bottom of a boat hull; a seat bottom pivotally mounted between the upright arms of the U-shaped seat frame; a brace pivotally connected to the seat bottom and adapted for attachment to the bottom of the U of the U-shaped seat frame to hold the seat bottom relative to the frame; a combination seat-back fastener and seat lock mounted on the upper portion of each of the arms of the U-shaped seat frame; each of said combination seat-back fasteners and seat locks including a seat-back bar, a longitudinal spacer perpendicular to the seat-back bar and arm, a frame rod perpendicular to the spacer and pivotally mounted in the upper portion of its respective seat frame arm, and a finger perpendicular to the rod and parallel to the seat-back rods; and a flexible seat back connected to the rod of each of the combination seat-back fasteners and seat locks.

3. A collapsible boat comprising, in combination; a quadrangular bottom; a quadrangular side having one edge sealingly fixed to one edge of said bottom; a quadrangular bow having one edge sealingly fixed to a second edge of the bottom and a second edge sealingly fixed to one edge of said side; a second quadrangular side having one edge sealingly fixed to a third edge of the bottom and a second edge sealingly fixed to one edge of the bow; a stern having one edge sealingly fixed to a fourth edge of the bottom; said stern having opposite edges sealingly fixed to respective edges of said sides; a quadrangular side panel having one edge sealingly and hingedly connected to one edge of the first-mentioned of said sides; a triangular side panel having one edge sealingly and hingedly connected to one edge of the quadrangular side panel; a quadrangular bow panel having one edge hingedly and sealingly connected to one edge of the triangular side panel; said bow panel having a second edge hingedly and sealingly connected

to one edge of the bow; a second triangular side panel having one edge hingedly and sealingly connected to one edge of the bow panel; a second quadrangular side panel having one edge hingedly and sealingly connected to one edge of the second triangular side panel and a second edge hingedly and sealingly connected to one edge of the second side; a third triangular side panel having one edge hingedly and sealingly connected to one edge of the second quadrangular side panel; a quadrangular stern panel having one edge hingedly and sealingly connected to one edge of the third triangular side panel and one edge hingedly and sealingly connected to one edge of the stern; a fourth triangular side panel having one edge hingedly and sealingly connected to one edge of the quadrangular stern panel and a second edge hingedly and sealingly connected to one edge of the first-mentioned quadrangular side panel; a seat bracket mounted on the bottom, a U-shaped seat frame having the bottom of the U positioned in the seat bracket, a seat bottom pivotally mounted between the upright arms of the U-shaped seat frame; a brace pivotally connected to the seat bottom and connected to the bottom of the U-shaped seat frame to hold the seat bottom relative to the seat frame; a combination seat-back fastener

and seat lock mounted on the upper portion of each of the arms of the U-shaped seat frame; each of the combination seat-back fasteners and seat locks including, a seat-back bar, a longitudinal spacer perpendicular to the seat back and arm, a frame rod perpendicular to the spacer and pivotally mounted in the upper portion of its respective seat-frame arm, and a finger perpendicular to the rod and parallel to the seat-back rods; a seat back connected to the rod of each of the seat locks, and a seat catch mounted on each of the quadrangular side panels for locking the seat lock to the side panels by means of the respective catch fingers.
